UNITED STATES PATENT OFFICE.

WILLIAM R. GILLIES, OF CHICAGO, ILLINOIS, ASSIGNOR TO THE EQUIPMENT SPECIAL-TIES COMPANY, OF CHICAGO, ILLINOIS, A CORPORATION OF ILLINOIS.

DRAIN TRAP.

Application filed August 6, 1923. Serial No. 655,922.

To all whom it may concern:

Be it known that I, WILLIAM R. GILLIES, a citizen of the United States, and resident of Chicago, in the county of Cook and State 5 of Illinois, have invented a certain new and useful Improvement in Drain Traps, of which the following is a full, clear, concise, and exact description, reference being had to the accompanying drawings, forming a 10 part of this specification.

My invention relates to a drain trap which is particularly suitable for installation upon railway refrigerator cars. Generally stated, it is the object of my invention to provide 15 a device of this class which is of sturdy construction and largely of sheet metal, which may be economically manufactured and readily installed, and which comprises improved devices for cleaning the trap whenever occasion requires.

One of the salient features of my invention resides in the provision of an improved agitator which is capable of both reciprocating and rotary motion, it being capable 25 of reciprocating motion to lift the cap of the drain pipe of the trap, and being capable of rotary motion to agitate and displace the dirt, sawdust, and other solid or semi-solid matter which collects in the trap 30 bowl.

Other features, objects and advantages of my invention will appear from the following detailed description, wherein reference is made to the accompanying drawings, in 35 which

Figure 1 is a fragmentary top plan view of a drain trap constructed in accordance with my invention;

Figure 2 is a vertical section taken on the 40 line 2—2 of Figure 1;

Figure 3 is a view similar to Figure 2, but illustrating a modified embodiment of my invention; and

Figure 4 illustrates a further modification 45 of the same.

Similar characters of reference refer to similar parts throughout the several views.

Referring first to Figures 1 and 2, at 50 10 I have illustrated the floor of a refrigerator car and at 11 a metal drain pan of the kind commonly employed in the bulkheads of such cars. The car construction so far as illustrated in the drawings is conventional, and need not be described in detail. The 55 drain pan is provided with a circular open-

ing 13 which registers with the open upper end of the drain trap bowl 14, which extends through an opening in the car floor and conveniently occupies a position between a contiguous pair of the timbers 60 which support the car floor.

The drain trap bowl 14 is formed in one piece from sheet metal, and is provided at its upper edge with an outwardly projecting marginal flange 15 which is attached 65 to the drain pan 11. As here illustrated, the flange 15 lies under the metal bordering the drain pan opening 13, and is secured to the drain pan by bolts 16. However, the flange 15 may be soldered as well as riveted 70 to the drain pan or the bolts and solder may be dispensed with and the flange may be secured to the drain pan in any other suitable manner, as for instance by welding.

It will be noted that the metal constituting the bottom of the bowl 14 is perforated and pressed upwardly to provide an upwardly projecting annular flange or hollow boss 17. Pressed very tightly into the flange 17 and having a liquid tight fit therewith, 75 is a pipe 18, the upper end of which is located a substantial distance above the bottom of the bowl; the lower end of the said pipe being located a substantial distance below the bottom of the bowl. The upper 80 end of the pipe 18 is preferably cut off in a plane oblique the axis of the pipe, as illustrated.

Disposed within the pipe 18 and preferably rigidly secured thereto by any suitable 85 means, as for instance rivets 19, is a second pipe of smaller diameter indicated at 20, which constitutes a guide for the combined agitator and cap lifter presently to be described. It will be noted that the upper end 90 of the smaller pipe 20 lies a substantial distance above the lowermost portion of the upper edge of the larger pipe 18; hence, the level of liquid in the trap bowl 14 will not rise to a point where said liquid will enter 95 the smaller pipe 20. Loosely disposed in the smaller pipe 20 is a combined agitator and cap lifter which is in the form of a metal rod 21 provided with an offset lower end 22 which serves as a handle for manipulating the device 21 for the purpose of lifting the drain pipe cap and for agitating the contents of the drain trap bowl in the manner presently to be explained. The upper 100 end of the rod 21 is turned laterally over the 105 110

edges of the pipes 18 and 20, and is then turned downwardly and then again outwardly and upwardly to provide the portion 23 which serves as an agitator arm.

5 At 24 I have illustrated a cap for the drain pipe 18, this cap being formed in one piece from sheet metal, and consisting of a circular top wall and a downwardly flaring side wall, the lower edge of the latter 10 normally lying in a plane a substantial distance below the lowermost portion of the upper end of the drain pipe 18. The cap 24 is hingedly secured to the drain trap bowl 14 by co-operating hinge members 25 and 26, 15 which are respectively secured to the cap 24 and the bowl 14 in any suitable manner, as for instance by rivets 26', the said hinge members 25 and 26 being provided with the usual loops for receiving a hinge pin, which 20 in the present instance is in the form of a cotter pin 27. It will be noted that the cotter pin is so located that it is readily accessible from the inside of the car.

The hinge devices hereinbefore described 25 and the device 21 normally hold the drain pipe 24 in the position illustrated in full lines in Figure 2.

In the use of the drain trap, sawdust, dirt, 30 and other solid and semi-solid matter collects in the bowl 14 and tends to prevent the free escape of water therefrom. This obstructing matter which thus gathers in the drain trap bowl must frequently be removed. The combined agitator and cap lifter 21 hereinbefore mentioned constitutes an 35 extremely effective means whereby a workman may clean out the drain trap without entering the car. In order to clean the trap, the workman grasps the handle portion 22 of the device 21, moves the latter to the dotted line position illustrated in Figure 2. When the device 21 is so raised the drain pipe cap 40 24 is swung to the dotted line position shown in the same figure. This movement of the drain pipe cap serves in a measure to disturb and agitate the solid and semi-solid contents of the drain trap bowl and also exposes the upper end of the drain pipe to such an extent that the obstructing material 45 may readily escape through the drain pipe. Further agitation of the solid and semi-solid material which accumulates in the drain trap bowl may be accomplished by turning the device 21 around a vertical axis, 50 the arm 23 being capable of movement through a substantial arc in close proximity to the bottom and side walls of the drain trap bowl, and serving effectively to dislodge any obstructing material which may 55 not be dislodged by the simple operation of lifting the drain pipe cap.

In some instances it may be desirable to imbed the drain trap bowl and the upper portion of the drain pipe 18 in heat insulat-

ing material. Such heat insulating material 65 is indicated at 28.

In Figure 3 I have illustrated an embodiment of my invention wherein the pipe through which the combined agitator and cap lifter extends is disposed alongside of, 70 and not within, the drain pipe 18. In this embodiment of my invention, the pipe 19 extends through and is fitted in the bottom of the drain trap bowl 14 similarly to the pipe 18, the upper end of the pipe 19 being 75 located a substantial distance above the top of the drain pipe 18. In this embodiment of my invention, the parallel pipes 18 and 19 are preferably so disposed that a horizontal line passing through their axes extends longitudinally of the car.

It is frequently desirable to provide the drain pipe traps of the kind herein illustrated with hingedly mounted inclined lower ends or chutes which insure that the liquid, often salty, which escapes from the drain trap, shall not come into contact with a journal bearing located in proximity to the lower end of the drain pipe. A suitable device for directing the escaping liquid outwardly from the lower end of the drain pipe 18 is illustrated at 29 in Figure 3. The device 29 need not be described in detail, as devices of this general character are now well-known in the art to which my invention relates.

The embodiment of my invention illustrated in Figure 4 is particularly advantageous because it dispenses with any necessity for a device of the kind illustrated at 100 29 in Figure 3. In the embodiment of my invention illustrated in Figure 4, the drain pipe 18 is disposed at an angle to the bottom of the drain trap bowl, the water escaping from the lower end of the drain pipe being 105 permitted to drop outside of the journal box associated with the car wheel illustrated at 30. In all other respects the structure illustrated in Figure 4 may be substantially identical with the structure illustrated in 110 Figures 1 and 2.

In all of the herein illustrated embodiments of my invention, the device 21 serves both to lift its associated drain pipe cap and to agitate the solid and semi-solid material 115 which collects in and obstructs its associated drain trap bowl.

Having thus illustrated and described a number of preferred embodiments of my invention, I do not limit myself to the precise arrangement and construction of parts herein shown and described, but wish to cover all equivalent embodiments of the invention as the same is defined by the appended claims.

What I claim is new, and desire to secure by Letters Patent of the United States, is:

1. In a drain trap, a bowl, a drain pipe,

- a hingedly mounted drain pipe cap and a combined agitator and lifter extending through said drain pipe, said combined agitator and lifter being capable of longitudinal movement to lift said cap and being capable of rotary movement to agitate solid and semi-solid matter accumulated in said bowl.
2. In a drain trap, a bowl, a drain pipe extending through the bottom of said bowl and terminating a substantial distance above the bottom of the latter, a second pipe also entering said bowl through the bottom thereof, and terminating above the top of the drain pipe, a hingedly mounted cap for said drain pipe, and a combined cap lifter and agitator extending through said second pipe, said agitator and cap lifter being capable of movement longitudinally of said second pipe to lift said cap and being capable of rotary movement to dislodge solid and semi-solid matter accumulated in said bowl.
3. In a drain trap of the class described, a bowl, a drain pipe entering said bowl through the bottom thereof, a hingedly mounted cap for said drain pipe, a second
- pipe also entering said bowl through the bottom thereof and terminating above the top of said drain pipe, a rod extending through said second pipe and normally constituting a support for said cap, said rod comprising an agitator arm disposed in said bowl, said rod being capable of longitudinal movement to lift said cap and being capable of rotary movement to dislodge solid and semi-solid matter accumulated in said bowl.
4. In a drain trap, a bowl, a drain pipe extending to the bottom of said bowl and terminating a substantial distance above said bottom, a cap for said drain pipe, said cap comprising a top wall and a downwardly flaring side wall, and hinge members for mounting said cap for movement relatively to the drain pipe around an axis located above said cap.

In witness whereof, I hereunto subscribe my name this 31 day of July, 1923.

WILLIAM R. GILLIES.
